(57) **CLAIM**

The ornamental design for a hurricane tie, as shown and described.

DESCRIPTION

FIG. 1 illustrates a perspective view of a hurricane tie. FIG. 2 illustrates another perspective view of the hurricane tie of FIG. 1.

FIG. 3 illustrates a right side view of the hurricane tie of FIG. 1.

FIG. 4 illustrates a left side view of the hurricane tie of FIG. 1.

FIG. 5 illustrates a top view of the hurricane tie of FIG. 1.

FIG. 6 illustrates a bottom view of the hurricane tie of FIG. 1.

FIG. 7 illustrates a rear view of the hurricane tie of FIG. 1; and,

FIG. 8 illustrates a front view of the hurricane tie of FIG. 1. The broken lines in the drawings illustrate portions of the hurricane tie and form no part of the claimed design.

1 Claim, 4 Drawing Sheets
